UNITED STATES PATENT OFFICE.

JOHN SLACK, OF BROOKLYN, NEW YORK, ASSIGNOR TO ABRAHAM G. JENNINGS, OF NEW YORK CITY.

DESIGN FOR A NET FABRIC.

Specification forming part of Design No. 5,270, dated September 19, 1871.

To all whom it may concern:

Be it known that I, JOHN SLACK, of the city of Brooklyn, in the county of Kings and State of New York, have invented a new and original Design for a Reticular Fabric; and I do hereby declare that the following is a full, clear, and exact description thereof, which will enable others skilled in the art to make and use the same, reference being had to the accompanying drawing forming part of this specification.

The drawing represents a face view of my improved new fabric.

This invention relates to a new arrangement of threads in net-work, whereby a new form and combination of meshes are produced. The de-

sign thus obtained consists of small lozenges *a a*, larger lozenges *b b*, and pentagons *c c*. The small lozenges are equilateral and are arranged in rows, but are in one direction (horizontally) divided from each other by the larger lozenges *b b*, and in the other direction (vertically) by the lines *d* that separate the several pairs of pentagons, as clearly shown in the drawing. The larger lozenges *b* are also equilateral, while the pentagons *c* have unequal sides, as shown.

I claim as my invention—

The design for a reticular fabric, as shown.

JOHN SLACK.

GEORGE W. MABEE,

ALEX. F. ROBERTS.

(76.)
